GASOLINE PRICE COMPUTER

Donald Norman Volger, 500 N. Florence, Burbank, Calif.

Filed July 15, 1964, Ser. No. 80,886

Term of patent 14 years

(Cl. D52—6)

FIG. 4.

FIG. 1.

FIG. 2.

FIG. 3.

FIG. 1 is a front elevational view of a gasoline price computer, showing my new design.

FIG. 2 is a rear elevational view thereof:

FIG. 2 is a rear elevational view thereof;
FIG. 3 is a front elevational view of a portion of the computer shown in FIGS. 1 and 2 with cover disc omitted; and

FIG. 4 is a side elevational view thereof.

FIG. 4 F

I claim:

The ornamental design for a gasoline price computer, as shown and described.
